UNITED STATES PATENT OFFICE.

EDWARD H. ZOLLAR AND CHARLES T. JOHNSON, OF CANAL DOVER, OHIO.

SAD-IRON.

1,273,566.

Specification of Letters Patent. Patented July 23, 1918.

Application filed October 21, 1912. Serial No. 726,878.

To all whom it may concern:

Be it known that we, EDWARD H. ZOLLAR and CHARLES T. JOHNSON, citizens of the United States, residing at Canal Dover, 5 county of Tuscarawas, and State of Ohio, have invented new and useful Improvements in Sad-Irons, of which the following is a specification.

Our invention relates to improvements in 10 that class of sad irons, which comprise among other things, a smoothing core and a removable shell and handle.

1st, to provide means for preventing the wooden member from turning on the metallic central member of the handle;

2nd, to provide means for preventing the respective end members of the handle from becoming detached from the shell;

3rd, to provide means for rigidly securing 20 the center post to the core; and

4th, to provide means for yieldingly and detachably connecting the head of the center post of the shell.

Our invention is further explained by reference to the accompanying drawings, in which—

Figure 1 is a side view of the core and handle and a longitudinal sectional view of the core inclosing shell.

30 Fig. 2 is a top view of the device, drawn on line $x-x$ of Fig. 1.

Fig. 3 is a side view partly in vertical section of the fastening plate, and

Fig. 4 is an end view of the hand piece 35 of the handle.

Like parts are identified by the same reference numerals throughout the several views.

1 is the core of a sad iron. 2 is the center post. The core 1 is provided with a vertical screw threaded aperture 3 for the reception of the threaded end 4 of the center post. 5 is a lock nut by which the center post is rigidly locked to the core. The center post 2 is provided with a head 6 beneath which the resilient fastening plate 7 is adapted to engage, when the shell is secured to the core. It will be understood that the fastening post 2 is first turned 50 down in the aperture 3, when the lock nut 5 is turned down firmly against the upper surface of the core 1, whereby the post is rigidly secured in said core and the liability of it becoming loose in or disengaged therefrom is avoided.

8 represents the wooden or fibrous hand

piece of the handle, which is rigidly secured to the central member 10 of such handle, as indicated by dotted lines. The hand piece 8 is provided at its longitudinal center with an aperture 12 for the reception of the central member 10 of the handle, and at its respective ends with grooves or notches 13 for the reception of the opposing surfaces of the end members 14 of the handle, 60 whereby when said hand piece is in place, the grooves 13 are adapted to engage upon the respective sides of the end members 14, whereby the hand piece 8 is prevented from turning on the central member 10. 70

15 is the core inclosing shell, which is preferably made of heavy resilient sheet metal and is pressed into the required shape to closely fit the upwardly converging member 16 of the core. The shell 15 is provided 75 with two apertures 17 for the reception of the threaded end members 18 of the handle, and said threaded end members are each provided with nuts 19, which have threaded bearings on said end members, whereby 80 when said end members 18 have been inserted in said apertures 17, they are securely held in place by turning down said nuts 19 on said end members, whereby the handle is rigidly and securely secured to the 85 core inclosing shell. The resilient locking plate 7 is pivotally connected to the upper surface of the shell by the pivotal bolt or rivet 20. Said shell 15 is provided with a central aperture 21 for the reception of the 90 fastening post 2 and said resilient fastening plate 7 is provided with a segmental recess 22, which is adapted to engage the upper end of said fastening post 2 beneath the head 6. 95

23 is an operating knob or hand piece by 100 which the resilient fastening plate 7 is moved into and out of engagement with said post. The fastening plate 7 is provided with an upwardly curved bearing surface 24, which is adapted to contact with the lower side of the head 6 of said fastening post as the resilient plate 7 is brought into engagement with said post, whereby the shell is forced downwardly and held in 105 yielding contact with the bead 25 of the core. By thus securing the hand piece 8 to the end members 14 of the handle, it is prevented from turning and such parts are rigidly secured together and the liability of their becoming loose or rattling is prevented. 110 Also the lock nut 5 prevents the liability of the post 2 from becoming loose in or de-

tached from the core 1 of the sad iron, while the nuts 19 impinge firmly against the under side of the shell, whereby the liability of the handle becoming loose or detached from the shell is prevented, while owing to the upward bend 24 of the fastening plate, the shell is forced into yielding contact with the core, whereby all of said cooperating parts are firmly and rigidly secured together and the liability of any of such parts becoming loose or detached, is obviated.

Having thus described our invention, what we claim as new and desire to secure by Letters Patent, is—

15. In a device of the described class, the combination with a smoothing core, an inclosing

shell, of a fastening lever pivotally connected at one end with said shell and provided upon one side with an upwardly curved resiliently yielding bearing surface and upon its opposite side with a recess, said recess being formed for the reception of the upper end of a fastening bolt, the lower end of which bolt is rigidly connected with said smoothing core.

25. In testimony whereof we affix our signatures in the presence of two witnesses.

EDWARD H. ZOLLAR.

CHARLES T. JOHNSON.

Witnesses:

EDWARD E. BUERKEL,

AARON WENGER.
